UNITED STATES PATENT OFFICE.

ARTHUR GEORGE LLOYD NEIGHBOUR, OF BRIGHTON, VICTORIA, AUSTRALIA.

MAGNETO IGNITION MACHINE.

Application filed April 2, 1926, Serial No. 99,249, and in Australia April 6, 1925.

This invention relates to magnetos employed for ignition purposes in internal combustion engines, and it has special reference to an improved magneto wherein the various coacting parts are mounted on or within an angularly displaceable structure or sleeve which maintains the parts in their most efficient positions at all points in the range of timing adjustments.

10 In prior constructions to obtain uniformity of sparking over the timing range, soft iron polar segments have been used which were positioned between fixed pole pieces of the permanent magnets and the rotating armature, and were mechanically connected with the operative cams of the interrupter so as to move synchronously therewith during timing adjustments. In some cases the soft iron polar segments have been fixed in 15 a sleeve of non-magnetic metal which was rotatively mounted between opposed fixed pole pieces magnetically associated with permanent magnets fixed to the frame of the machine.

20 25 In the prior patent of applicant No. 1,449,345, laminated polar segments or auxiliary pole pieces were mounted on a sleeve of non-magnetic material and were positioned between fixed pole pieces and an armature rotatively mounted within the sleeve. The sleeve was fitted in a housing or casting whereon the magnets and fixed pole pieces were mounted, and the armature, interrupter, and the distributor were supported by said sleeve, the rotary element of the distributor being carried on the armature. The collectors of the distributor were spaced 30 35 concentrically around the axis of the armature, and the distributor was accordingly of gearless construction.

40 In the present invention a non-magnetic timing sleeve is also employed, which in addition to the above mentioned parts has mounted or fixed upon it the permanent magnets, and is provided with an extension which supports both the stationary and moving elements of the distributor which is of gear driven construction and is operatively connected with the armature shaft.

45 50 55 The timing sleeve accordingly carries all the parts of the magneto and in effect the invention consists essentially in mounting a magneto in a housing adapted for attachment to an internal combustion engine, and in arranging and fixing the magneto in the housing in such manner that the timing

sleeve may be angularly adjusted therein for timing purposes.

In consequence of the mounting of the magnets on the timing sleeve, the fixed pole pieces are eliminated, and a very simple and strong housing can be employed to carry said sleeve. Moreover the efficiency of the magneto is increased by the correspondingly lower eddy current losses, and generally the machine is simplified in construction, is much decreased in size, and its cost of manufacture is considerably reduced.

In effecting timing adjustments the sleeve is angularly displaced in the housing, and the magnets and pole shoes, the operative cams of the interrupter, and the distributor are rotated to a greater or less extent about the axis of the armature, and when the operative cams effect separation of the contacts 75 of the interrupter the armature can be arranged to occupy the most efficient position with respect to the pole shoes independently of the setting of said timing adjustments.

A difficulty commonly met with in magnetos, and due to there being no provision for effecting timing adjustments of the distributor and more particularly noticeable at high speeds, is that sparking is apt to occur between the rotating distributor brush and the distributor collector segments, thereby causing "tracking" or burning and wear of the portion of the insulation over which the brush travels.

This has been obviated to some extent by increasing the peripheral length of the collector segments but this necessarily increases the size of the distributor block or stator.

In the present invention as the distributor is moved during the timing adjustments of 95 the sleeve planetary movement of the distributor gear is set up about the driving pinion on the armature shaft. Advantage is taken of this planetary motion to compensate for variable timing of the spark and 100 it enables the distributor brush to occupy the most favourable position relatively to the collector segments at all points in the range of timing adjustments.

In this invention there is no limit to the 105 range of such adjustments, and it will be found that the timing sleeve may be rotated or angularly displaced to any extent in the housing without affecting the intensity of the spark generated at a given speed. Moreover, in any position of said sleeve, when the interrupter contacts separate, the distributor

brush will always occupy the same position with respect to the collector segments. It accordingly follows, that the magneto may be operated in any position of the timing sleeve in the housing, and that a range of timing adjustments of any required extent may be obtained in all positions of said sleeve.

Furthermore, by advancing or retarding the timing sleeve the setting of the ignition range off an engine may be accurately adjusted, even when the engine is running, and without disturbing the magneto from its seating and without the use of adjustable driving couplings hitherto employed for this purpose.

In the drawings illustrating the invention:

Figure 1, is a view in longitudinal section 20 of a magneto ignition machine.

Figure 2, is a view in transverse section on the line 2—2 in Figure 1.

Figure 3 is a view, partly in elevation and partly in section, on the line 3—3 Figure 1, 25 drawn to a smaller scale and showing the timing sleeve in various positions.

Figure 4 is a view in sectional plan on the line 4—4 Figure 1.

In these drawings the numeral 5 designates a housing made of a suitable non-magnetic metal, such as for example aluminium, or an alloy thereof suitable for die-casting.

The housing 5 can be of cylindrical form and it can be provided with base flanges 6, 35 shewn by broken lines in Figure 2, parallel to its axis and arranged to form a base when the magnet is to be base-mounted on an engine, or it can be provided with feet or lugs 7 for the same purpose, or again it can 40 be furnished with an enlarged flange 8 at one end for attachment to an engine when the magneto is to be spigot-mounted thereon.

The housing 5 may be bored cylindrically and of uniform diameter from end to end, 45 but preferably said housing is provided with internal peripheral flanges or collars 9 at its opposite ends. These flanges may be made of the same internal diameter as shewn, or they may be of different diameters if required, and in some cases said flanges may 50 be made as separate bushings of suitable metal adapted to fit recesses formed in the housing 5 to accommodate them.

The housing 5 accommodates a sleeve 10 55 of non-magnetic metal which at one end 11 is shouldered to bear against an end of the housing 5 and at the opposite end is provided with a detachable flange or plate 12 by means of which said sleeve is retained in position.

The sleeve 10 can be provided with an end plate 13 at one end, and with an inturned flange (not shewn) at the opposite end, and said end plate and inturned flange form supports for the armature bearings as described 60 in the applicant's Patent No. 1,449,345, above

referred to. Alternatively, the sleeve 10 can be provided (as shewn) with detachable covers at both ends which likewise accommodate the armature bearings. The flange or plate 12 and the end plate 13 form such 70 detachable covers.

In opposite sides of the sleeve 10 and symmetrically positioned about a diametrical plane therethrough are formed slotted openings into which are fitted soft iron pole 75 shoes 14, preferably of laminated structure.

Arcuately formed magnets 15, preferably made of highly magnetic cobalt steel, are fixed as by screws 16 to the portions of the sleeve 10 between the pole shoes 14, and the 80 magnets 15 at their opposite ends overlap the pole shoes 14, or they may fit recesses (not shewn) therein.

The magnets 15 are arranged with their ends of like polarity in contact with the same 85 pole shoe, so that the opposed pole shoes 14 have opposite polarities and a bi-polar magnetic field is thereby formed in which an armature 17 and associated condenser 17^a, 90 both of well known construction, rotate.

The armature 17 is provided with a primary winding 17^b and a secondary winding 17^c, but the details of construction thereof are unimportant in so far as the present 95 invention is concerned.

Two or more magnets may be used side by side, and compound magnets may be employed if required. The outer peripheries of the magnets 15 may be ground or otherwise made to fit snugly within the housing 5, but preferably a small clearance as shewn is provided therebetween.

The sleeve 10 is provided with rings 18 made of suitable metal and constructed to 100 rotatively fit the inturned flanges or collars 9. The rings 18 may be made of somewhat greater diameter than the magnets 15 in order that the sleeve 10 may be easily inserted into the housing 5, as will be readily understood. For this purpose also, the ring 18 at the end of the sleeve 10 adjacent the rear or driving end of the magneto may be made of less diameter than the ring 18 adjoining the shouldered end of said sleeve.

The laminations forming the pole shoes 14 can be cast in position in the sleeve 10 during manufacture or they may be retained in the slotted openings in said sleeve by the overlapping ends of the magnets 15.

As previously mentioned the distributor 120 is carried on the sleeve 10 and is advantageously moved therewith during timing adjustments.

The sleeve 10 accordingly is provided with an enlarged extension or chamber 19 on 125 which is mounted the stationary part or stator 20 of the distributor and which accommodates the moving part or rotor 21 thereof and the gearing operating the same.

The distributor may be of any suitable 130

construction, and it may be of the form shewn in the drawings attached hereto and described and illustrated in the applicant's prior Patent No. 1,613,053, wherein the distributor rotor 21 is driven by a bevel gear 22 operatively engaging a bevel pinion 23 on the shaft 24 of the armature 17. Similar means may also be used to those described and illustrated in said Patent No. 1,613,053 for disruptively discharging high tension secondary currents between the armature 17 and the distributor rotor 21.

If the distributor rotor 21 is adapted to be driven by spur gearing from the armature shaft 24, the distributor may be made in accordance with the alternative distributor construction described and illustrated in the applicant's Patent No. 1,613,053, above referred to.

20 When a distributor operated by bevel gearing, as shewn in the drawings attached hereto, is employed, the sleeve 10 is provided with an inclined extension 19^a in and upon which the stator 20 and rotor 21 are mounted.

As hereinbefore mentioned the distributor is moved about the axis of the armature 17 during timing adjustments of the sleeve 10. This movement of the distributor sets up 30 planetary motion of the distributor gear 22 about the pinion 23 on the armature shaft 24, and the distributor rotor 21 is accordingly rotated more or less by timing adjustments of the sleeve 10.

35 Advantage is taken of this planetary movement of the gear 22 to compensate for variable timing of the spark, and it enables the distributor brush 25 to be mounted in such manner that the full width thereof 40 evenly faces and occupies the same symmetrical position with respect to each distributor collector 26 in succession, at each spark discharge in all positions of the sleeve 10 in the housing 5.

45 It is accordingly unnecessary to provide any overlapping of the brush 25 and collectors 26 in timing the former with respect to the latter, and the collectors 26 may accordingly be of less peripheral length and 50 they may be arranged closer to each other than has hitherto been the practice, thereby enabling the distributor stator 20 to be correspondingly reduced in size.

The primary interrupter may be of any 55 suitable construction, and preferably of the type having a rotary element 27 fixed to the armature shaft 24 and provided with the usual pivoted arm 30 adapted by impact with cams 28 fixed to the end plate 13 to separate 60 contacts 31 and 32 in the primary circuit, the contact 32 being connected with the primary winding 17^b in the usual manner.

In order that the angular adjustment of 65 the sleeve 10 and the parts thereon may be readily affected, an arm 29 is fixed to or cast

integral with the sleeve 10, or the extension 19 thereof, and is adapted for connection with and operation by controls in the usual manner, as shown in Figure 3.

It will be obvious to those skilled in the art to which the invention relates that the sleeve 10 with magnets 15, pole shoes 14, armatures 17, condenser 17^a, interrupter (comprising a rotary element 27, pivoted arm 30, contacts 31 and 32, and stationary cams 28), and distributor (having a rotor 21 and stator 20), forms a complete multi-spark magneto. It will also be understood that the housing 5 forms a support in which the magneto so constructed is mounted, and so in which the sleeve 10 with magnets 15, pole shoes 14, and cams 28 may be angularly adjusted for timing purposes about the armature 17 and the rotary element 27 and the parts thereon.

Moreover, as the pole shoes 14 and the cams 28 bear a fixed relationship to each other by reason of their respective attachment to the sleeve 10 and the end plate 13 fixed thereto, and as the rotary element 27 of the interrupter is secured to the shaft of the armature 17; it will be obvious that the armature 17 will always occupy the same position relatively to the pole shoes 14 when the pivoted arm 30 coacts with the cams 28 to separate the contacts 31 and 32 to interrupt the primary circuit, irrespective of the position of the timing sleeve 10 in the housing 5.

Accordingly by arranging the pivoted arm 30 of the rotary element 27 to coact with the cams 28 to break or interrupt the primary circuit when the armature occupies its most efficient position with respect to the pole shoes 14 and the current in the primary circuit attains its maximum value; the best spark generated at a given speed will be obtained in all positions of the timing sleeve 10.

It has been shown above that the spark generated by the magneto at a given speed is independent of the position of the timing sleeve 10 in the housing 5, and that the distributor brush 25 occupies a constant position with respect to the collectors 26 during spark discharges in all positions of said sleeve in the housing 5.

Accordingly the magneto may be operated independently of the position of the timing sleeve 10, and the latter may be positioned so that the inclined extension 19^a thereof and the distributor thereon may be located vertically or horizontally or in an inverted position, as shown in Figure 3, or in any other required position.

Moreover, in any position of the timing sleeve 10, a considerably greater timing range can be employed than is possible with magnetos of ordinary construction, and the timing sleeve 10 may be actuated through the arm 29 to angularly displace said sleeve

through a greater range than the usual 30 degrees of advance adjustment, and through 10, 15, or more degrees of retard adjustment without in any way affecting the quality of the spark.

Furthermore, by advancing or retarding the timing sleeve 10, the setting of the ignition range of an engine may be accurately adjusted. For this purpose an adjustable member may be provided in the control linkage connected to the arm 29.

Summarized briefly, a magneto constructed in accordance with the foregoing, is of simple construction, comparatively small in size and of light weight, is capable of an unrestricted range of timing adjustments, is adapted for adjustment without removal from its seating on an engine to enable the setting of the ignition thereof to be adjusted as and when required, and in operation is adapted to maintain its parts in their most efficient positions and to furnish a spark of maximum intensity in fully advanced or retarded positions and in all intermediate positions.

I claim:—

1. A magneto having a housing adapted for mounting in fixed position, and having the whole of its magnetic, electrical, and operating parts mounted in and on a structure fitting and angularly adjustable in the housing and adapted in any adjusted position to maintain said parts in their most efficient relationship.

2. A magneto having a housing adapted for mounting in fixed position, and having its magnetic elements and its current generating, interrupting, collecting and distributing members mounted in and on a structure fitting and angularly adjustable in the housing and adapted in any adjusted position to maintain said elements and members in their most efficient relationship.

3. A magneto having a housing adapted for attachment to an internal combustion engine, and having magnets, pole shoes, an armature, an interrupter, and a distributor mounted in and on a structure fitting within the housing and angularly adjustable therein for timing purposes.

4. A magneto having a housing adapted for attachment to an internal combustion engine, and having magnets, pole shoes, an armature, an interrupter, and a distributor mounted in and on a timing sleeve detachably fitting the housing and angularly adjustable therein.

5. A magneto having a housing, means on the housing for attaching the same to an internal combustion engine, a timing sleeve fitting within the housing; magnets, pole shoes, an armature, an interrupter, and a distributor mounted in and on the timing sleeve; a member detachably fixed to the timing sleeve and adapted to retain said

sleeve in the housing, and means for angularly displacing the timing sleeve in said housing.

6. A magneto comprising a housing, a timing sleeve fitting the housing and angularly adjustable therein, an armature rotatable in the sleeve, magnets, pole shoes, a distributor, and interrupter cams mounted on the timing sleeve and adjustable therewith about the armature, and an interrupter supported by said sleeve and rotatable therein.

7. A magneto embodying magnets, pole shoes, an armature, an interrupter, a distributor, distributor collectors and a rotary distributor brush, a timing sleeve on which said parts are mounted, and a housing in which the timing sleeve is angularly adjustable and in any adjusted position thereof is adapted, when the interrupter is in operation, to maintain the pole shoes in their most efficient position relative to the armature and the rotary brush in a constant position with respect to the collectors.

8. In a magneto, a timing sleeve, oppositely disposed openings in the timing sleeve, pole shoes in the oppositely disposed openings, and magnets fixed to and movable with the timing sleeve and adapted to contact with the pole shoes and to retain the same in said openings.

9. In a magneto, a timing sleeve, pole shoes in the timing sleeve, and arcuately formed magnets fixed to the timing sleeve and arranged in peripheral contact with said sleeve and the pole shoes.

10. In a magneto, a timing sleeve, an armature therein, magnets fixed to the timing sleeve, and pole shoes in said sleeve having their outer face in contact with the magnets and their inner faces in direct magnetic association with the armature.

11. In a magneto, a timing sleeve, an armature therein, oppositely disposed pole shoes in the timing sleeve, and magnets having their ends of one and the same polarity fixed to the timing sleeve and in contact with one of the pole shoes and their ends of the other polarity in contact with the opposite pole shoes to form an angularly adjustable bi-polar magnetic field in which the armature rotates.

12. In a magneto, a housing, a timing sleeve detachably fitting the housing, an enlarged extension at one end of the timing sleeve adapted to support stationary and rotary elements of an interrupter and a distributor and to form a shoulder on said sleeve, and a flange detachably fixed to the opposite end of the timing sleeve and coacting with the shoulder to retain the timing sleeve in said housing.

13. In a magneto, a housing having means formed integral therewith arranged for mounting the housing in fixed position,

and a timing sleeve annularly adjustable in the housing carrying magnets and pole shoes therefor, said sleeve having an axial extension arranged for supporting stationary and rotary interrupter elements and having a lateral extension arranged for supporting stationary and rotary distributor elements.

14. In a magneto, a timing sleeve, an armature rotatable therein, magnets fixed to the timing sleeve, a rotary element of an interrupter rotatable with the armature, operative cams of the interrupter on the timing sleeve, pole shoes in said sleeve having their outer faces in contact with the magnets and their inner faces in direct magnetic association with the armature, and an arm on the timing sleeve to angularly adjust said sleeve and the magnets and pole shoes about the armature, and the rotary interrupter element relative to the interrupter operating cams.

15. A magneto having a housing adapted for attachment to an internal combustion

engine, a timing sleeve fitting within the 25 housing, a shoulder at one end of the timing sleeve, a detachable flange at the opposite end of the timing sleeve, magnets fixed to and arranged in peripheral contact with the timing sleeve and positioned within the 30 housing, pole shoes fixed in the timing sleeve in contact with the magnets, an enlarged extension on the timing sleeve, an end plate fixed to the enlarged extension, an armature, an armature shaft, rotary elements of 35 an interrupter on the armature shaft, stationary cams of the interrupter on the end plate, a distributor having a stator and a rotor mounted on the enlarged extension, gearing within the enlarged extension 40 operatively connecting the rotor with the armature shaft, and an arm on the enlarged extension adapted to effect angular adjustments of the timing sleeve.

In witness whereof I hereunto affix my 45 signature.

ARTHUR G. L. NEIGHBOUR.
